UNITED STATES PATENT OFFICE.

CARLOS J. REEVES, OF DUNCAN, OKLAHOMA.

HEAVING PLUG.

Application filed June 26, 1928. Serial No. 288,469.

This invention relates to heaving plugs and it is an object of the invention to provide a device of this kind which, when applied within a well casing, fits snugly there-
5 in and thereby effectively serves to keep water, cement, sediment or other foreign matter from passing by the applied plug up into the casing.

Another object of the invention is to pro-
10 vide a device of this kind provided at its upper portion with an outstanding washer or gasket adapted to have close contact with the casing when the plug is in applied position and also wherein the lower portion of
15 the plug is adapted to have a plate attached thereto operating for the same purpose as the washer.

The invention consists in the details of construction and in the combination and ar-
20 rangedment of the several parts of my im-
proved heaving plug whereby certain im-
portant advantages are attained and the de-
vice rendered simpler, less expensive and
25 otherwise more convenient and advan-
tageous for use, as will be hereinafter more
fully set forth.

The novel features of my invention will hereinafter be definitely claimed.

In order that my invention may be the
30 better understood, I will now proceed to
describe the same with reference to the ac-
companying drawing, wherein:

Figure 1 is a view partly in section and partly in elevation of a heaving plug con-
35 structed in accordance with an embodiment
of my invention;

Figure 2 is a sectional view taken sub-
stantially on the line 2-2 of Figure 1;

Figure 3 is a fragmentary view of the
40 bottom disc illustrating one of the bayonet
slots in the marginal flange of said disc.

As disclosed in the accompanying drawing, 1 denotes a hollow cylindrical body or shell having its upper end 2 closed with the
45 opposite or lower end of the bore of the body or shell open. At diametrically op-
posed points the body or shell 1 is provided with the longitudinally directed slots 3
through which are directed the outer end
50 portions of the clamping arms or dogs 4. The inner end portions of these arms or dogs 4 are pivotally connected with a rod 5 disposed transversely through the body or shell 1 and supported thereby.
55 These arms or dogs 4 are constantly urged

toward the horizontal by an expandible member 6, preferably a coil spring, inter-
posed between the closed end 2 of the body or shell 1 and the inner or pivoted end por-
tions of the dogs or arms 4. 60

The closed end 2 is provided with a re-
duced extension 7 upon which is adapted to
be threaded a cap 8 and which cap serves
to clamp to the face 9 surrounding the ex-
tension 7 a washer or gasket 10. This 65
washer or gasket 10 projects beyond the periphery of the body or shell 1 for close
contact with the wall of the casing into
which the plug is applied to provide an ef-
fective medium to keep water, cement, sedi- 70
ment or other foreign matter from passing
by the plug up into the casing.

Disposed over the lower or open end of
the body or shell 1 is a disc 11 having its
marginal portion defined by a flange 12 sub-
stantially at right angles to the disc 11 and
which flange has close contact with the pe-
riphery of the body or shell 1 adjacent to
its lower or open end. The inner wall of
the flange 12 is provided with the bayonet 80
slots 14 into which are adapted to be en-
gaged the outstanding pins or lugs 15 car-
ried by the lower portion of the body or
shell 1 whereby the disc 11 may be effec-
tively held in applied or working position 85
with respect to the body or shell 1 yet be
readily and conveniently applied or re-
moved. The flange 12 of the disc 11 is also
adapted to have close contact with the wall
of the casing into which the plug is applied 90
to prevent passage of matter around the
plug up into the casing while the disc 11
closes the lower open end of the body or
shell 1 and prevents any matter entering
such body or shell. 95

The outer ends of the arms or dogs 4
are provided with the beveled teeth 16 which
are adapted to have biting action upon the
inner wall of the well casing so that when
in applied position the device is effectively 100
held against upward movement within the
casing, said beveled teeth offering no hin-
drance or obstruction to the device when
being lowered within the casing.

From the foregoing description it is 105
thought to be obvious that a heaving plug
constructed in accordance with my inven-
tion is particularly well adapted for use
by reason of the convenience and facility
with which it may be assembled and oper- 110

ated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

10 I claim:—

A heaving plug comprising a body having a tubular portion open at an end, the wall of said tubular portion being provided at substantially diametrically opposed

points with openings, securing means mounted within the body and extending outwardly through the openings, a disc disposed over the open end of the body and provided with a flange surrounding the adjacent end portion of the body, means for holding the disc and flange in applied position, and a washer carried by the opposite end portion of the body and projecting beyond the periphery thereof.

In testimony whereof I hereunto affix my signature.

CARLOS J. REEVES.
